MULTIPLE DIAPHRAGM PUMP

Auguste Guiot, Paris, France, assignor to Etablissements Guiot, Paris, France, a society of France

Application December 12, 1951, Serial No. 261,355

Claims priority, application France
December 21, 1950

1 Claim. (Cl. 103—150)

1

The present invention relates to multiple diaphragm pumps of the kind including at least two diaphragms at a distance from each other and housed in a pump body in such manner that between each of the side walls of said body and each of the diaphragms there is formed a chamber in communication, through suitable valve means, with the fluid (either liquid or gaseous) intake conduit and with the fluid discharge conduit, the space between the diaphragms serving to house the pump driving means through which the reciprocating displacements of said diaphragms are obtained.

The object of the present invention is to provide a pump of this type which is better adapted to meet the requirements of practice than those known at the present time, and in particular which has a substantially continuous delivery and is easier to manufacture.

My invention consists chiefly in constituting the pump driving means by at least one eccentric disposed in the space existing between the diaphragms, this eccentric being located inside parallel annular parts which are respectively rigid with the respective diaphragms and the edges of which are kept in contact with the eccentric through elastic means whereby continuous rotation of the eccentric causes successive displacements of the respective diaphragms in the direction of suction when the projecting portion of the eccentric is moving along the inner edge of the annular part toward the point thereof which is at the greatest distance from the diaphragm in question, and successive displacements of these membranes in the discharge direction are obtained through the effect of elastic means and when the projecting portion of the eccentric moves away from said point.

Other features of my invention will appear in the course of the following description of some embodiments thereof with reference to the accompanying drawings, given merely by way of example and in which:

Figs. 1, 2 and 3 show, respectively in vertical axial section, in plan view (with portions cut away and portions in horizontal axial section), and in cross section on the line III—III of Fig. 1, a diaphragm pump according to the invention.

Fig. 4 is a section, similar to Fig. 3, of a modification.

Referring first to Figs. 1 to 3, the pump includes two parallel diaphragms 1 and 2 housed in the body 3 of the pump so as to leave a space 4 between them. Each diaphragm is constituted by a sheet of circular outline made of a flexible ma-

2

terial such as a plastic matter, leather, natural or synthetic rubber and so on, this sheet carrying on one of its faces a disc 5 of metal or another rigid material which covers nearly all the area of the face in question.

The edge of this sheet is tightly held between the pump body proper and a side plate fixed in a removable manner on said body 3, for instance by means of screws or bolts. As the pump includes two diaphragms 1 and 2, they are located on either side of the body proper 3 and are held in position by two removable side plates 6 and 7, respectively.

Between the outer face of each diaphragm 1, 2 on which is applied metallic disc 5 and the wall of the corresponding side plate, there is formed a chamber 8 (Fig. 3), 9 (Fig. 2) into which flows the fuel to be delivered. Chambers 8 and 9 may be put in communication, through passages such as 10 and 11 (Fig. 2) provided in the pump body, with a common intake 12 and through similar passages such as 13 and 14 (Fig. 3) with a common outlet 15. In passages 11 are provided automatic inlet valves 16 and in passages 13 automatic delivery valves 17. At the places where the diaphragms extend across passages 13, one or several holes 13a are provided in these diaphragms.

In the space 4 between the two diaphragms 1 and 2 is housed the mechanism through which are obtained the reciprocating movements of said diaphragms and, according to the invention, this mechanism is arranged in such manner that the diaphragms act successively to draw in the liquid into chambers 8 and 9 alternately. Likewise, the liquid is discharged from these chambers alternately. For this purpose, I make use of an eccentric 18 mounted at the end of shaft 19 extending into the body 3 of the pump through one wall thereof so that the axis of this shaft is in the vertical plane of symmetry of said body and intersects the straight line passing through the respective centers of diaphragms 1 and 2.

A circular ring 18a is journalled on eccentric 18 with the interposition of a roller bearing 18b (Fig. 1). Shaft 19 is driven by a suitable motor, for instance an individual electric motor 20, through a speed reducing gear 21.

On the inner face of each diaphragm 1, 2, and in particular on a disc 5a carried by this face, are fixed, close to the center of the membrane, one or several flat annular parts which surround eccentric 18.

In the example shown, diaphragm 2 carries two annular parts 22 and 23 adjoining each other along a plane passing through a diameter of this

diaphragm 2. Diaphragm 1 carries two similar parts 24 and 25 located on either side of parts 22—23 and slightly distant therefrom. Of course, parts 22 and 23 might be combined into a single one.

These annular parts are fixed to the metallic discs 5a of the corresponding diaphragms through suitable means, either in a removable manner and for instance as shown by means of pins 26 engaged in lugs 27 provided on the inner faces of these discs and in holes provided in said parts, or permanently, for instance by welding on discs 5a.

Eccentric 18 extends at least over the width of the whole of the parallel and juxtaposed annular parts 22 to 25, so that it can act, when turning, on these parts in the manner hereinafter described.

Every flat annular part forms an aperture the diameter of which is greater than that of the eccentric and the inner edge of which is provided, advantageously but not necessarily, with a flat projection 28, 29 located in the portion of said inner edge at the maximum distance from the corresponding diaphragm 2, 1. The flat projections 28 of parts 22 and 23 are therefore located on the left of eccentric 18 (Fig. 3) and the flat projections of parts 23 and 25 on the right of this eccentric.

Between diaphragms 1 and 2, or rather between their discs 5a, I interpose a plurality of helical springs 30, for instance two springs disposed in a diametral plane of the diaphragms and the ends of which are engaged on projections 31 of the inner faces of discs 5a. Owing to the action of these springs, the inner edges of annular parts 22—23—24—25 remain constantly in contact with the eccentric at points located in the axial plane of shaft 19 which is parallel to the axes of springs 30.

In Fig. 1, 32 designates a roller bearing housed in the pump body 3 and in which shaft 19 is journalled; 33 and 34 are lubrication conduits, closed by a plug 35.

The pump thus constituted works as follows: Motor 20 drives shaft 19 and eccentric 18. The projecting portion (i. e. the portion of maximum radius) of the eccentric comes for instance in contact first with the flat projections 29 of annular parts 24 and 25 which are carried by diaphragm 1, and this diaphragm is pulled toward the right of Fig. 3, which increases the volume of chamber 8. Fuel is therefore drawn into this chamber through passages 12, 10 and 11, the corresponding valve 16 opening automatically. Simultaneously with this, diaphragm 1 exerts, through springs 30, a thrust on diaphragm 2 which is therefore also moved toward the right, thus reducing the volume of chamber 9. The fuel present in said chamber is expelled past valve 17 and through passages 13, 14 and 15 toward the place where it is to be used. When the eccentric has rotated through 180°, its portion of maximum eccentricity acts upon the flat projections 28 of annular parts 22 and 23, which pulls diaphragm 2 toward the right hand side of Fig. 3, so that fuel is now drawn into chamber 9. Simultaneously this diaphragm 2 pushes, through springs 30, diaphragm 1 in the same direction, thus causing the fuel previously admitted into chamber 8 to be expelled from the pump. Chambers 8 and 9 therefore successively admit fuel and discharge it, in alternating fashion.

Of course, I might, according to my invention, distribute any desired number of diaphragms about shaft 19, these diaphragms being located

in planes parallel to the axis of this shaft and at the same distance therefrom, the suction and delivery strokes taking place, when the eccentric is rotating, in response to the cooperation of the portion of maximum radius of this eccentric with projections, such as 28 and 29, of annular parts rigid with the respective diaphragms.

Fig. 4 shows an embodiment of my invention which, for most of its elements, is similar to that above described. The feature which differentiates this construction from that of Figs. 1 to 3 is that, in order to keep every annular part 22, 24 in contact with eccentric 18, I make use of a helical pulling spring 40 one end of which is fixed at 41 to the center of the outer disc 5 of the corresponding diaphragm. The other end of this spring is fixed to the pump body, for instance to a pin 42 disposed diametrically in a tubular portion 43 of the side plate 6 (or 7) of the pump body. A cap 44 is screwed on said tubular portion 43.

In the example shown, the action of spring 40 is of predetermined force, but it might of course be made adjustable.

It is clear that the pull exerted by spring 40 on the corresponding diaphragm 1 or 2 constantly keeps the flat edge 28 or 29 of annular part 22 or 24 in contact with eccentric 18.

Such a spring arrangement has the advantage of dispensing with the presence of compression springs in the central portion of the pump, where it may be difficult to house them when the pump includes more than two diaphragms.

Furthermore, this arrangement makes it possible to use an odd number of diaphragms, since it is no longer necessary to group them in pairs of two diaphragms facing each other.

Finally, springs 40 are easily reached and adjusted if necessary.

In all cases, a pump according to my invention has the advantage of running at the desired speed noiselessly and without requiring much power. It supplies fluid instantaneously and in a practically continuous manner. Its operation does not depend upon the physical conditions of the fluid.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claim.

What I claim is:

A pump which comprises, in combination, a pump body, at least two diaphragms in said body disposed at a distance from each other so as to leave an interval between them and having their edges fixed to the inner wall of said body so as to form with said body a variable volume chamber on either side of said interval, a fluid inlet and a fluid outlet carried by said body, conduits in said body arranged to connect each of said chambers with said fluid inlet and said fluid outlet, intake and delivery valves in said conduits, annular parts carried by said diaphragms in fixed positions with respect thereto respectively on the sides thereof turned toward each other, the inner contour of each of said annular parts including a flat inward projection extending parallel to the diaphragm which carries said part in the portion of said contour which is at the greatest distance from said last mentioned diaphragm, a shaft journalled in said body having its axis

parallel to both of said diaphragms and located in said interval, an eccentric carried by said shaft engaged inside said annular parts, and spring means for urging against said eccentric the flat projection of each annular part which is at the greatest distance from the diaphragm which carries said annular part, said spring means including a pulling spring interposed between the outer face of each diaphragm and the pump body, to urge said diaphragm away from said eccentric.

AUGUSTE GUIOT.
